BUNG FOR A BARREL

Henry O. Wilcox, Denver, Colo., assignor to Denver Plastics, Inc., Lakewood, Colo., a corporation of Colorado

Filed Dec. 10, 1968, Ser. No. 14,860

Term of patent 14 years

Int. Cl. D9—02

U.S. Cl. D9—254

FIG. 1

FIG. 3

FIG. 4

FIG. 2

FIG. 5

FIG. 6

FIGURE 1 is a bottom perspective view of a bung for a barrel embodying my new design;

FIGURE 2 is a top perspective view thereof;

FIGURE 3 is a top plan view thereof;

FIGURE 4 is a side elevation view thereof;

FIGURE 5 is a bottom plan view thereof; and

FIGURE 6 is a vertical sectional view taken through the line 6—6 of FIGURE 3.

I claim:

The ornamental design for a bung for a barrel, as shown.
